LAWN SPRINKLER

John D. Beinert, Babylon, N.Y., assignor to International
Patent Research Corp., New York, N.Y., a corporation
of New York

Filed Nov. 19, 1963, Ser. No. 77,486

Term of patent 7 years

(Cl. D91—1)

FIG. 1 is a perspective view of a lawn sprinkler showing my new design;

FIG. 2 is a fragmentary side elevational view thereof;

FIG. 3 is a fragmentary top plan view of the sprinkler of FIG. 2;

FIG. 4 is a rear elevational view thereof; and

FIG. 5 is a front elevational view thereof, with the sprinkler arm and actuating elements omitted for the convenience of illustration.

The essential features of my design reside in those features shown in full lines.

I claim:

The ornamental design for a lawn sprinkler, as shown and described.
